UNITED STATES PATENT OFFICE.

HARRIS HIGGINS, OF CHICAGO, ILLINOIS.

FURNACE-DOOR.

SPECIFICATION forming part of Letters Patent No. 268,889, dated December 12, 1882.

Application filed October 13, 1882. (No model.)

To all whom it may concern:

Be it known that I, HARRIS HIGGINS, of Chicago, county of Cook, and State of Illinois, have invented certain new and useful 5 Improvements in Furnace-Doors, of which the following is a full, clear, and exact description, that will enable others to make and use the same, reference being had to the accompanying drawings, and to letters of reference marked 10 thereon, forming a part of this specification.

This invention relates to an improvement on Letters Patent No. 238,006, the object being to make additions and changes in the construction of the device, so that the slide covering 15 the draft-openings in the furnace-door is automatically adjusted to admit air into the combustion-chamber, as will be hereinafter more fully set forth in detail.

Figure 1 is a front elevation of a boiler-front embodying my improvement; Fig. 2, a vertical transverse section of a furnace-door in the plane xx , Fig. 1; and Fig. 3, a view in perspective of my improved feature.

Referring to the drawings, A represents the 25 furnace-door proper, the general features of which are of the same form and construction as that set forth in the patent above referred to. A general description of the door will therefore be omitted, the description in this case being confined to my improvement and the parts 30 relating thereto.

The furnace-door is provided with the elongated openings a , for the admission of air into the furnace.

35 B represents a slide set in the face of the door, and is adapted to have a vertical movement. This slide is composed of a series of horizontal bars, b , connected by end pieces running at right angles, which correspond in number to the draft-openings.

The back or stationary end of the lever C is pivoted to the back end of the door, while the opposite end is prolonged so as to project beyond the end of the door, as shown in Fig. 1 45 of the drawings, which is not the case in the patent referred to above. The slide B and lever C are connected near their longitudinal center by the link D. The lever C is connected at a point near the loose end with the pis-ton-rod a' of the dash-pot E.

The projecting lug F is provided with the flange b' , which is bolted to the furnace-front. This projecting lug is provided with the shoulder d , against which abuts the inner end of the adjustable sword-arm H, pivoted to the lug F. 55 This arm is wedge-shaped, the upper surface being a rising plane, as shown in Fig. 3 of the drawings, and may be thrown upward in a vertical plane out of the way, but cannot drop down below the position shown in Fig. 3, by 60 reason of the stop a^2 .

In the patent referred to above the slide covering the draft-openings in the face of the door had to be raised by hand each time that fresh fuel was added to the fire, as that is the time 65 that the draft-apertures in the face of the door are required to be wide open, and then gradually closed, as the varying wants of the fire may require, by means of the piston descending in the dash-pot, which is filled with oil or other 70 suitable liquid body.

The heel or back end of the arm H is provided with the offset b , which permits the outer end of the lever C to drop down as the piston in the dash-pot descends. Now, when the furnace-door is opened the projecting end of the lever C passes underneath the arm H, and when the door is closed the end of the lever C rises on the upper side of the arm H and automatically raises the slide and uncovers the 80 draft-openings in the face of the door.

Having thus described my invention, what I claim as new, and desire to secure by Letters Patent, is—

In a furnace-door, the combination, with the 85 slide B and the dash-pot E, of the lever C, having a suitable connection therewith, and the adjustable arm H, whereby the act of closing the door has the effect of automatically raising said slide and uncovering the draft-openings provided for the admission of air into the combustion-chamber, substantially as described.

HARRIS HIGGINS.
